DESIGN FOR AN EMBOSSED LEATHER FABRIC OR THE LIKE

Joseph Frischer, Long Beach, N. Y.

Application December 30, 1939, Serial No. 89,242

Term of patent 7 years

To all whom it may concern:

Be it known that I, Joseph Frischer, a citizen of the United States and resident of the county of Nassau, city of Long Beach, and State of New York, have invented a new, original, and ornamental Design for an Embossed Leather Fabric or the like, of which the following is a specification, reference being had to the accompanying drawing, forming part thereof.

What I claim is:

The ornamental design for an embossed leather fabric or the like, substantially as shown.

JOSEPH FRISCHER.
